REGULATION

Application filed January 28, 1930. Serial No. 423,913.

My invention relates particularly to steam power plants and more generally to regulation of flow of fluids. In one particular phase of my invention it relates to automatic regulating mechanism for proportioning flow of feed water to the flow of steam, with special reference to plants having a steam generating unit supplying steam to different prime movers.

Amongst the objects of my invention are: To properly proportion the flow of feed water to the flow of steam in a steam plant; to provide a novel method and apparatus for the regulation of flow of feed water in accordance with flow of steam in a steam plant; to provide a novel and efficient flow proportioner; to proportion flow in a steam plant between sections thereof; and to provide adjustments for flow control in connection with my novel flow proportioner.

Further objects and the nature and advantages of the invention will become apparent on consideration of the following specification taken in conjunction with the accompanying drawings showing, more or less diagrammatically, steam plant apparatus embodying flow-regulating mechanism in accordance with the invention.

With respect to the figures of the drawings:

Fig. 1 is a diagrammatic representation of a steam plant embodying the invention;

Fig. 2 shows one member of a rotatable regulating device;

Fig. 3 shows a cooperating member of the regulating device;

Fig. 4 is a more or less diagrammatic representation of the regulating device;

Fig. 5 shows a steam plant having a plurality of turbine units to which the invention is applied; and

Fig. 6 shows a valve in a pipe for adjusting flow.

Referring to Fig. 1, reference character 10 designates a source of steam or steam generating unit which may consist of one or more boilers fired in any of various ways. The steam generating unit 10 supplies steam to conduit 12, which is connected to a turbine or other type of prime mover or steam

consumer 13. The turbine 13 is shown as driving an electric generator 14. A condenser 15 is connected to receive steam from the turbine. The condensate is conducted through conduit 16 by means of a pump 17 55 therein and is discharged into a feed water heater 18 supplied with steam through conduit 19. The water flows through conduit 21 and pump 20, which may be a multi-stage pump, and thence through the conduit 22 60 back to the vapor source 10. Pump 20 is a flow-controlling element in the liquid conduit 21-22 since the speed thereof determines or controls the rate of flow of liquid therein. Pump 20 is driven by a motor 23, 65 the speed of which is controlled in a manner which will now be described.

In conduit 22 is an orifice plate 24 constituting a flow-measuring element. As is known, the difference of pressure on the two sides of an orifice may be used to measure or register flow. The impulse tubes 25 and 26 are connected to conduit 22 at the two sides of the orifice plate 24. The impulse tube 26 carries a higher pressure than the impulse tube 25 due to the drop of pressure through the orifice.

Referring to Fig. 4, the two impulse tubes 25 and 26 connect into casing 27 on opposite sides of a diaphragm 28 in such manner that the diaphragm 28 is subjected to the differential of pressure existing on the two sides of the orifice plate 24 in conduit 22. Variations of this differential of pressure move the center of diaphragm 28 and are utilized to rotate a member 29 (see also Fig. 3) through suitable power-transmitting mechanism such as rod 30, lever 31, rod 32, lever and rack 33, and pinion 34. Obviously, any ratio of leverage may be used 90 which will best suit the circumstances, and the arrangement of parts may be varied.

In conduit 12 is an orifice plate 35 which likewise serves the purpose of registering or measuring flow. Connected to conduit 12 95 at each side of orifice plate 35 are impulse tubes 36 and 37. These impulse tubes transmit the steam pressure on the two sides of orifice plate 35 to the two sides of diaphragm 38 in chamber 39. The differen- 100

tial of pressure is utilized to move the center of diaphragm 38, and consequently the rod 40 and leverage members 41, 42 and 43, to rotate a member 44 (see also Fig. 2), which 5 member 44 is situated within member 29. Again in this respect, the leverage may be of various forms, and I have only indicated 10 diagrammatically how the differential force may be transmitted between the diaphragm 15 38 and the member 44.

Members 29 and 44 constitute a switch or 20 switches for controlling an electric circuit which in turn controls the speed of the motor 23. The side members 45 and 46 of 25 member 29 are made of electric conducting material. Member 29 is formed with a non-conducting member, which may be the back piece such that there is no electric conduction between members 45 and 46. Two electric 30 leads 47 and 48 are connected to the members 45 and 46, respectively. In the outer end of member 29 are two screws 49 and 50, constituting electric contacts which are adapted to engage the contact points 51 35 and 52, respectively, on member 44. Member 44 is made of electric conducting material. A lead 53 is connected to member 44. The leads 47, 48 and 53 are connected to a known type of regulator 54, which varies 40 the speed of motor 23. The members 29 and 44 are pivoted at 55 and may be arranged in conjunction with a dial 56 to show the position thereof.

The operation of the apparatus is as follows: Suppose that the rate of supply of 45 steam to turbine 13 increases as, for example, due to an increased opening of the steam supply valve to the turbine due to a centrifugal governor thereon responsive to 50 speed. The greater rate of flow of steam through conduit 12 results in a greater pressure differential on the two sides of orifice plate 35. This means that the pressure will be relatively higher in tube 36 than in tube 55 37. The result of this will be an increase of pressure on the upper side of diaphragm 38 relative to the pressure on the under side thereof. This will cause a counter-clockwise movement of member or arm 44. As a result of this, contact point 52 on member 44 contacts the screw contact member 50 of arm or member 29. This contact causes flow of 60 electricity to the regulator 54 as a result of which the speed of electric motor 23 is increased and more water is pumped by the pump 20. The result of more pumping by the pump 20 is to increase the pressure differential through orifice plate 24 so that the pressure is relatively higher in tube 26 than 65 in tube 25. This causes an upward movement of diaphragm 28, as a result of which arm 29 is moved in counter-clockwise direction, thus moving the contact 52 away from the contact 50. The regulator 54 is such 70 that, having increased the speed of motor 23,

this speed will stay constant at the increased rate until the regulator 54 is again energized by further electric contact. Consequently, as will be seen, the increase in steam flow has resulted in an increased speed of the pump 20, thus increasing the rate of flow of water through conduit 22.

Conversely, assume that the rate of flow of steam through conduit 12 decreases. The pressure differential across orifice 35 will 75 then be less. This will move diaphragm 38 upwardly as a result of which arm 44 will move in clockwise direction. Contact point 51 will then contact screw 49 and electric connections will be made such that regulator 80 54 will decrease the speed of motor 23. This will decrease the rate of flow of feed water in conduit 22 as a result of which the pressure differential across the orifice 24 will 85 decrease whereby diaphragm 28 will move downwardly, thus rotating arm 29 clockwise so that contact 49 moves away from contact 51 and the relay circuit is again broken.

It will be seen from the above that so 90 long as the flow of liquid bears a definite relation to the flow of steam, the arm 44 will remain midway between the side contacts of arm 29, irrespective of the position of the two arms on the scale member 56. 95 If, however, the proportion varies, electric contacts will be made by the arms which will readjust the flow to a proper proportion, and which will thus bring back the regulator to the intermediate position of equilibrium. 100

In place of using the pump as the flow-controlling element, the flow-controlling element may be a valve as shown at 57, the pump then running at constant speed. Such valve will be operated by a motor 58 or 105 otherwise to decrease the valve opening when the steam flow decreases, and conversely, to increase the valve opening when the steam flow increases. This valve is connected to the regulator by electric wires 59. I have shown switches 60 and 61 to indicate that the valve or the pump may be used alternately as the elements for controlling the rate of flow. When the valve is used, if the diaphragm 38 moves downwardly due to 110 increased steam flow, and contact point 52 contacts screw 50, the electric energization is such that the valve 57 is opened to a wider position.

In order to take care of variations over 115 a period of time or to make desired adjustments, I have provided valves 62 and 63 arranged in parallel with the orifice plates 24 and 35, respectively. One or the other of these valves may be used, but I prefer to 120 use only the valve 62 arranged in parallel with the orifice plate 24. This valve is preferably provided with a pointer 64, as shown in Fig. 6, and with a scale 65 to indicate how the valve should be turned to 125 130

obtain higher or lower boiler water level. Turning the valve in one direction will cause the boiler water level to gradually increase so long as the valve is left in that position, 5 while turning it in the opposite direction will have the opposite result. It will be understood that this valve and its pipe, in parallel with the orifice plate 24, constitute a permanently open by-pass.

10 The regulating arrangement is particularly advantageous in connection with boiler plants wherein there are a number of boilers all connected to a common steam header and a number of turbines all taking steam 15 from the same steam header. This is still more particularly true of plants using open feed water heaters as disclosed in my co-pending application Serial No. 399,152, filed October 12th, 1929, Pat. No. 1,857,332, 20 granted May 10, 1932. I have illustrated in Fig. 5 the type of plant which I refer to and in combination with which my regulator is particularly advantageous. In Fig. 5 the steam generating unit 10 supplies 25 steam to the header 12. A plurality of turbines 13 and 13a receives steam from the common header through separate pipes. The turbines have condensers 15 and 15a respectively, and the pumps 17 and 17a 30 pump the condensate through the heaters 18 and 18a. Steam is extracted from the turbines through conduits 19 and 19a. Pumps 20 and 20a force the feed water through conduits 22 and 22a into the common feed 35 pipe 66 for supplying feed water to the various boilers of the steam generating unit.

Other parts including the regulating apparatus are the same as shown in Fig. 1, 40 wherefore they are marked with like reference characters, those pertaining to the turbine 13a being marked additionally with the letter a.

Assume first that an installation as shown 45 in Fig. 5 has no regulating devices for proportioning the feed water flow to the steam flow. Assume now that the load on turbine 13a is heavier than on the turbine 13. This means that the pump 20a will have a higher 50 discharge pressure than the pump 20 due to the fact that the pumps operate on a pressure difference. The result of this, since the pumps are connected to pump into a common header 66, would be that the pump 20a would pump practically all the water 55 and the pump 20 would pump practically no water, thus offsetting the coordination between steam and water flow in both the parts of the system. However, with my regulating 60 arrangement, the flow of feed water will be made independent of the discharge pressure of the pumps and will be proportioned to the amount of steam flowing to the respective turbines. The manner of operation 65 of this arrangement is the same as described

in connection with Fig. 1, wherefore it need not be repeated here.

While the wiring between the flow regulator 56 and the flow control device 57 and the motor controller 54 has been shown in its simplest form, for the sake of clearness, it is to be understood that the electrical system may include any of the well known devices for decreasing the amount of current to be handled by the regulator contacts or for preventing hunting or other undesirable characteristics, such devices including relays, circuit interrupters, etc.

While I have described certain arrangements and certain constructions, it will be understood that the invention is not limited to specific constructions of apparatus or to specific plant layouts.

Having thus described my invention, what I claim is:

1. Apparatus of the character described comprising a first conduit, a second conduit, a flow-measuring element in each of said conduits, a flow-controlling element in one of said conduits, a movable member responsive to variations of flow in the first conduit, a movable member responsive to variations of flow in the second conduit, said movable members having spaced and contactable relations and means operable on contact of the movable members to control said flow-controlling element to move the movable members out of contact.

2. Apparatus of the character described comprising a conduit for flow of vapor, a conduit for flow of liquid, a flow-controlling element in the liquid conduit, a movable member responsive to variations of flow in the vapor conduit, a movable member responsive to variations of flow in the liquid conduit, said movable members having spaced and contactable relations and means operable on contact of the movable members to control said flow-controlling element to move the movable members out of contact.

3. Apparatus of the character described comprising a plurality of conduits for flow of fluid and means for controlling flow of fluid in one conduit in accordance with flow in another conduit comprising a first rotatable member having a plurality of contact points, a second rotatable member mounted coaxially with said first rotatable member and adapted to have contacting and non-contacting positions with respect to said first rotatable member and means responsive to flow in different conduits for rotating said members.

4. Apparatus of the character described comprising a plurality of conduits for flow of fluid and means for controlling flow of fluid in one conduit in accordance with flow in another conduit comprising a first rotatable member having a plurality of contact points, a second rotatable member mounted

- coaxially with said first rotatable member and adapted to have contacting and non-contacting positions with respect to said first rotatable member, means responsive to flow in different conduits for rotating said members, and an indicating dial for showing the position of the rotatable members.
5. Apparatus of the character described comprising a plurality of conduits for flow of fluid and means for controlling flow of fluid in one conduit in accordance with flow in another conduit comprising a first rotatable member having a plurality of contact points, a second rotatable member mounted coaxially with said first rotatable member and adapted to have contacting and non-contacting positions with respect to said first rotatable member, means including flow measuring devices responsive to flow in different conduits for rotating said members, and controllable by-passes around the flow measuring devices.
10. Apparatus of the character described comprising a first conduit, a second conduit, a flow measuring element in each of said conduits, a flow controlling member in said second conduit, a first regulating member responsive to flow in said first conduit and having a different given position for each 15 value of flow in said first conduit, a second regulating member responsive to flow in said second conduit and having independent movement with respect to said first regulating member and having a different given position for each value of flow in said second conduit, said first regulating member and said second regulating member being movable in the same direction on like change in flow in the respective conduits and means 20 for altering the flow controlling member dependent on relative positions of the first and second regulating members.
25. In testimony whereof I have affixed my signature.
30. RALPH C. ROE.
